UNITED STATES PATENT OFFICE.

HENRY L. SCHWARZENBERG, OF CLEVELAND, OHIO.

DESIGN FOR A KITCHEN UTENSIL.

SPECIFICATION forming part of Design No. 27,614, dated August 31, 1897.

Application filed June 26, 1897. Serial No. 642,547. Term of patent 3½ years.

To all whom it may concern:

Be it known that I, HENRY L. SCHWARZENBERG, of Cleveland, Cuyahoga county, Ohio, have invented and produced a certain new and useful Design for a Kitchen Utensil, of which the following is a specification, reference being had to the accompanying drawings, illustrating the design.

Figure 1 is a top plan of the design. Fig. 2 is a side elevation. Fig. 3 is a transverse section on either one of lines 3-3, Fig. 2, looking inwardly.

My design for a kitchen-tool comprises a single piece of sheet metal stamped into the shape required to form two upwardly-turned and outwardly-inclined heads or members A A' at opposite ends, respectively. Head A terminates centrally and at its upper extremity in a point a, instrumental in picking eyes out of potatoes, &c., and said head A is also provided with two upwardly-projecting flanges a' a', arranged at opposite sides, respectively, of the head and diverging inwardly, and useful as scrapers for cleaning pots, &c. Said head A is provided also with a slot a², that extends transversely of the device and has its outer side wall turned downwardly a trifle to form a paring-knife a³. The other upwardly-turned head A' of the device

has its outer edge rounded transversely of 30° the device to form a scraper A², and is provided also with two upwardly-projecting flanges A³ A⁴, arranged at opposite sides, respectively, of the head, and diverging inwardly from opposite ends, respectively, of 35° the aforesaid rounded edge and forming pot-cleaners. Said head A is provided also with a slot A⁴, extending transversely of the device and having its outer wall turned down far enough to form a cutter or slicer A⁵. The 40° device's central portion A⁶, that forms a web or yoke that connects the two heads together, is concavo-convex in transverse section, narrowest at its central portion, and enlarges in width from the said portion toward each head. 45° Said web is provided at each end with two reinforcing-ribs A⁷, extending longitudinally of the device and diverging outwardly.

What I claim is—

The design for a kitchen utensil, substantially as herein shown and described.

In testimony whereof I sign this specification, in the presence of two witnesses, this 17th day of June, 1897.

HENRY L. SCHWARZENBERG.
